UNITED STATES PATENT OFFICE.

EWALD G. BAUM, OF NATICK, MASSACHUSETTS, ASSIGNOR TO SEAL-KAP COMPANY, OF NATICK, MASSACHUSETTS, A CORPORATION OF MASSACHUSETTS.

MILK-BOTTLE CAP.

Application filed February 5, 1923. Serial No. 616,874.

This invention relates to caps more particularly designed for closing milk bottles and has for one of its objects the provision of a cap which may be sealed against the usual shoulder of the bottle on which the cardboard disk is commonly seated, against the wall of the bottle neck immediately above this shoulder and also extend over the edge of and below the shoulder without the loss of milk in case the bottle is initially filled level with the shoulder.

A further feature of the invention relates to means for maintaining the cap sealed in a secure manner, the cap and sealing member forming in effect a truss structure which offers considerable resistance to the deformation necessary to effect removal of the cap from the bottle.

For a more complete understanding of this invention together with further objects and advantageous details and combinations of parts, reference may be had to the accompanying drawings in which—

Figure 1 is a top plan of a cap as applied to a bottle.

Figure 2 is a fragmentary section on line 2—2 of Figure 1.

Figure 3 is an inverted plan of the cap detached.

Figures 4, 5, and 6 are views similar to Figures 1, 2, and 3, respectively, except that the bottle is not shown, Figure 5 being a section on line 5—5 of Figure 4.

Figures 7, 8, and 9 are views similar to Figures 4, 5, and 6, respectively, showing the sealing means applied to a different form of cap, Figure 8 being a section on line 8—8 of Figure 7.

Figure 10 is a transverse section through a further modified form of cap.

Referring to the form shown in Figures 1, 2, and 3, the cap C comprises an annular pouring lip housing portion 1 which is shown as corrugated over the upper edge of the bottle mouth. Immediately within this pouring lip housing is an annular shoulder portion 2 which is arranged to be seated on the annular ledge 3 of the bottle on which the disk of cardboard commonly used for closing the bottles may be seated. Beneath the ledge 3 the bore of the bottle is flared outwardly for a short distance as shown at 4. At 8 is shown a bore-covering portion of the cap which is connected to the shoulder portion 2 by means of an annular corruga-

tion 9 substantially semi-circular in cross section which extends over the edge of the ledge. As this corrugation 9 extends somewhat below the ledge 2, should the bottle be filled up to the ledge, this corrugation then would displace some of the contents. For this reason the bore-closing portion within the corrugation is raised slightly above the level of the shoulder 2 so as to afford a space into which the contents so displaced may flow so that in forcing the cap on the bottle none of the contents is forced out from beneath the cap and lost. As the corrugation 9 bears over the inner edge of the bottle ledge 3 it permits a more efficient seal to be effected therewith than if contact were only against the upper face of this ledge.

Further in order to hold the cap securely in position a disk 10 may be forced downwardly within the pouring lip housing its perimeter resting against and forcing outwardly the inner wall of the pouring lip housing, the bottle pouring lip at this point flaring downwardly and outwardly. This disk is preferably forced to a position within the pouring lip housing and then its edge and the inner face of the housing spread outwardly against the inner face of the pouring lip by a suitable die. When the disk is finally in its position, its central portion bears against the upper face of the cap within the corrugation 9 and its edge may be, though not necessarily, slightly upwardly bent to engage firmly within the lip housing.

This disk bearing on the upstanding portion of the pouring lip housing maintains it in sealing contact with the wall of the bottle mouth.

In Figures 4, 5, and 6 a preferred construction of cap is shown in which the pouring lip housing 1 is constructed as before as well as the shoulder 2 which engages on the bottle ledge. Instead of the corrugation 9, however, the bore-covering portion is bent downwardly over the bottle shoulder as at 12 and then is formed in substantially cone shape, the central portion thereof being flat as at 13 and raised upwardly above the level of the lower face of the shoulder 2 sufficiently to permit liquid displaced by the portion 12 when the cap is placed in position to flow therebeneath so as not to be forced out of the bottle. With this form also a disk 10 may be forced within the housing 1, its central portion resting on the 110

flat top 13 of the bore-covering portion and its edge engaging the inner wall of the pouring lip housing. With this construction, since the portion 13 is raised upwardly above the portion 2, the disk 10 when in position is domed or upwardly convexed or dished at its center but to a less extent than the bore-covering portion. The disk 10 and bore-covering portions, which together form a laminated bore-covering portion, are in contact at their centers but are held spaced adjacent their perimeters by the annular connecting strut formed by the portions 2 and 12. This causes a truss effect to be produced between the sealing disk and the cap, as may be seen clearly in Figure 5, which is very resistant to deformation so that the cap is very securely held in position. In this case also the marginal portion of the disk 10 may be slightly upwardly turned by its engagement with the pouring lip housing.

In Figures 7, 8 and 9 the sealing disk 10 is shown as applied to a cap of the form shown in my reissued patent No. 15,491 dated November 21, 1922. In this case, however, the bore-covering portion is maintained in its upwardly dished form after it has been sealed on the bottle instead of somewhat downwardly dished as shown in that patent. These figures are merely used to show the application of the sealing disk 10 to this type of cap by which a tighter sealing engagement of the cap to the bottle may be effected. In this form as well as in the forms shown in Figures 1 to 6 the disk presents a substantially flat upper surface on which printing or advertising matter may be applied.

In Figure 10 is shown still another modification, in which the annular corrugations 9 shown in Figures 1, 2, and 3 are utilized together with the conical bore-covering portion illustrated in Figure 5. In this case, however, the bore-covering portion shown at 15 is less pronouncedly conical than in the form shown in Figure 5 since a certain part of the axial dimensions of the cone are taken up by the corrugation. This type of cap also may be sealed by forcing a flat disk 10 into position against the center of the upper face of the bore-covering portion and engaging and forcing outwardly the inner wall

of the pouring lip housing, a truss construction similar to but somewhat less pronounced than that shown in Figure 5 being produced.

Having thus described certain embodiments of this invention, it should be evident to those skilled in the art that various modifications and changes may be made therein without departing from its spirit or scope as defined by the appended claims.

I claim:

1. A bottle cap for a bottle having an internal annular ledge below its top, which comprises a bore-covering portion having a part adjacent its margin arranged to overlie the inner edge of the ledge and project therebelow within said ledge and having its central part projecting above said ledge.

2. A bottle cap for a bottle having an internal annular ledge below its top, which comprises a bore-covering portion having a part adjacent to its margin arranged to overlie the inner edge of the ledge and project therebelow within said ledge, and having its central part projecting above said ledge and provided at said margin with an upwardly extending pouring lip housing engaging over the upper edge of the bottle mouth.

3. A bottle cap having an upwardly convex bore-covering portion, an annular upstanding marginal portion terminating in a pouring lip housing, and a disk engaging at its periphery within said upstanding portion to maintain said upstanding portion in sealing contact with the wall of the bottle mouth, said disk being in contact with the upper face of said bore-covering portion only at its center.

4. A bottle cap having an upwardly convexed bore-covering portion, annular marginal portions upstanding from said bore-covering portion, and a disk having its central portion engaging the upper face of the central portion of said bore-covering portion and its periphery engaging with said upstanding marginal portion, whereby said upstanding portion is maintained in sealing contact with the wall of the bottle mouth, said disk and bore-covering portions being spaced apart intermediate said central portion and the periphery of said disk.

In testimony whereof I have affixed my signature.

EWALD G. BAUM.
